(57) **CLAIM**

The ornamental design for a table, as shown and described.

DESCRIPTION

FIG. 1 is a perspective view of a table.

FIG. 2 is a front elevation view thereof. A rear elevation view is a mirror image of the front elevation view.

FIG. 3 is a right side elevation view thereof.

FIG. 4 is a bottom plan view thereof.

FIG. 5 is a cross-sectional view taken along the line 5-5 in FIG. 3; and,

FIG. 6 is a cross-sectional view taken along the line 6-6 in FIG. 3.

(Continued)

The broken lines shown in the drawings illustrate portions of the table that form no part of the claimed design.

1 Claim, 6 Drawing Sheets
